UNITED STATES PATENT OFFICE.

JOSEPH M. MALLOY, OF PHILIPSBURG, PENNSYLVANIA.

WINDOW-SASH BALANCE.

SPECIFICATION forming part of Letters Patent No. 635,332, dated October 24, 1899.

Application filed August 30, 1898. Serial No. 689,888. (No model.)

To all whom it may concern:

Be it known that I, JOSEPH M. MALLOY, a citizen of the United States, residing at Philipsburg, in the county of Centre and State of Pennsylvania, have invented a certain new and useful Improvement in Window-Sash Balances, of which the following is a specification.

My invention relates to a new and useful improvement in combined window-sash balances and burglar-alarms, and has for its object to provide exceedingly simple and effective devices of this description which when applied to a window will facilitate the raising and lowering of the sash by counterbalancing the same without the use of ropes or weights; and a further object of my invention is to so construct and combine a burglar-alarm with the balancing mechanism as to cause the same to be sounded should the sash be moved in either direction, and yet permit the cutting out of the alarm when the window is to be raised or lowered from the inside.

With these ends in view this invention consists in the details of construction and combination of elements hereinafter set forth and then specifically designated by the claims.

In order that those skilled in the art to which this invention appertains may understand how to make and use the same, the construction and operation will now be described in detail, referring to the accompanying drawings, forming a part of this specification, in which—

Figure 1 is an elevation of a portion of a window and sash, a part thereof being broken away so as to illustrate the application of my improvement thereto; Fig. 2, an enlarged view of my improvement as applied to a window frame and sash; Fig. 3, a section of the spring-drum; Fig. 4, a detail view of a portion of the adjusting-plate, showing a swinging latch for holding the drum against rotation prior to the insertion of the sash; and Fig. 5 is an enlarged view showing the construction and arrangement of the burglar-alarm and its connection with the balancing mechanism.

In carrying out my invention as here embodied, A represents an escutcheon-plate which is secured to the window-frame within the groove in which the sash B slides, and this plate has attached thereto the adjusting-plate

C by means of the screws D, which are swivelled in the plate A, their heads being exposed so that a screw-driver may be applied thereto for adjusting the plate C. The plate C carries the brackets E, which extend inward and have rectangular slots formed therein for the reception of the flattened ends of the spindle G. The spring-drum H is mounted upon this spindle, so as to freely revolve thereon, and one end of the spring I is attached to said spindle, while the outer end thereof is attached to the drum, as indicated at J, so that when the drum is revolved in one direction the spring will be wound and thereby store a certain amount of force, which will become active when the drum is released, causing the latter to revolve in a reversed direction. The sash B has secured along the edge thereof a rack-bar F, which is adapted to mesh with the gear K, carried by the drum, and in practice it is preferable that this arrangement shall be duplicated upon the opposite side of the sash in order that the action of the device may be balanced. From this description it will be obvious that a sash thus fitted will to a certain extent be counterbalanced by the spring I, so that it may be raised without undue exertion or may be lowered, which latter movement will wind the spring by revolving the drum, and thus store the power for assisting in again raising the sash. The screws D furnish sufficient adjustment to bring the gear K into proper mesh with the rack-bar F, and should at any time the sash shrink or swell the gear may be again adjusted in this manner.

A latch L is secured upon the turn-post M, which is journaled in the plate C, and the outer end of this post passes through the escutcheon-plate A and is slotted for the reception of a screw-driver. The object of this latch is to hold the drum by engagement with the gear-teeth prior to the insertion of the sash within a window, and thus facilitate the winding of the spring to the proper tension before said sash is placed in position; but after the rack-bar is entirely in mesh with the gear this latch is swung out of engagement with the gear-teeth, thereby freeing the drum, so that it may be revolved in either direction with the raising or lowering of the sash.

O represents a bell, which is secured upon

the hollow shank P by means of the radial arms Q, and this shank is journaled in a bushing R. Passed through this shank is the spindle S, the inner portion thereof being 5 journaled in a bracket T, and a pinion U is secured upon the inner end of this spindle and meshes with the gear K, so that any movement of this gear will cause the pinion to revolve, and on account of the difference in 10 size between the gear and the pinion the latter will revolve at a high rate of speed. The outer end of the spindle S carries the clappers V, the arms of which are of spring material, so that when the spindle is revolved 15 these clappers will strike the lugs W, formed upon the bell, thus causing the bell to ring rapidly, as is well understood.

The shank P is provided with a flange at its inner end, as indicated at X, and interposed between this flange and the inner end 20 of the bushing R is a coil-spring Y, the action of which is to normally hold the shank in the position shown in Fig. 5; but this spring will permit of the shank being drawn outward to 25 a limited degree, which movement will carry the pinion U out of engagement with the gear K, and thereby cut out the alarm, so that the sash may be then raised and lowered without sounding an alarm, from which it is obvious 30 that a person upon the inside of the sash may raise and lower the same without sounding the alarm simply by grasping the bell and drawing it outward sufficiently to carry the shank and the spindle S outward to disengage 35 the pinion from the gear, when the sash may be raised and lowered in the ordinary manner. The releasing of the bell will permit the spring Y to return the parts to their normal position and in so doing reengage the 40 pinion U with the gear. This feature of my improvement makes a most effective burglar-alarm, since the same cannot be tampered with from the outside, while the alarm must be sounded by any movement of the sash in 45 either direction, thus affording perfect protection to the occupants of the room.

The cost of my improvement is comparatively small, and it is readily applied to a

window, while it has many advantages over the ordinary ropes and weights and accomplishes the result of balancing the sash equally as well. 50

Having thus fully described my invention, what I claim as new and useful is—

1. In combination, a rack carried by a sash, 55 a drum, a gear-wheel, and a spring, a spindle for supporting the drum, a spindle carrying a gear taking motion from the gear of the drum, a bell and clappers carried by the spindle, substantially as described. 60

2. In combination, a sash, a rack, a gear-wheel meshing with the rack, a drum, a spring, 65 a gear-wheel meshing with the first-named gear-wheel, a spindle, clappers carried by the spindle, means for allowing the spindle to be drawn out to disengage the gear-wheels, and a spring for holding the parts normally in engagement, substantially as described.

3. In combination, a sash, a rack, a gear-wheel meshing with the rack, a drum, a spring, 70 a gear-wheel meshing with the first-named gear-wheel, a spindle, clappers carried by the spindle, means for allowing the spindle to be drawn out to disengage the gear-wheels, a latch for engaging the teeth of the gear-wheel, 75 and a spring for holding the parts normally in engagement, substantially as described.

4. In combination with a sash-balance of the character described, a burglar-alarm consisting of a spindle, a gear carried thereby 80 meshing with the gear of the balancing mechanism, clappers carried by the outer end of the spindle, a bell properly arranged relative to said clappers, a shank journaled around said spindle and carrying the bell, and a 85 spring for holding the shank in its normal position but permitting its outward movement, as specified.

In testimony whereof I have hereunto affixed my signature in the presence of two sub- 90 scribing witnesses.

JOSEPH M. MALLOY.
